CARD GAME PEG BOARD

Frank I. Smythe, 715 Tam-O-Shanter Ave.,
Sun City Center, Fla. 33570

Filed Dec. 26, 1973, Ser. No. 427,463

Term of patent 14 years

Int. Cl. D21—01

U.S. Cl. D34—13 A

FIG. 1

FIG. 2

FIG. 3

FIG. 4

FIG. 5

FIG. 6

FIG. 1 is a plan view of a preferred embodiment of the card game peg board showing my new design;

FIG. 2 is a side elevational view of the embodiment shown in FIG. 1, with a part broken away to show one of the sockets; and

FIGS. 3—6 are plan views, to a reduced scale, of peg boards each having modified plan peripheral configurations.

I claim:

The ornamental design for a card game peg board, as shown and described.
